UNITED STATES PATENT OFFICE

2,180,523

SMOOTHING IRON RESERVOIR

Frank J. Horton, Detroit, Mich.

Application February 10, 1937, Serial No. 125,056

5 Claims. (Cl. 38—94)

My invention relates to a new and useful improvement in a sprinkling device for use on smoothing irons and has for its object the provision of means whereby the user of the iron 5 may sprinkle the fabric in front of the iron prior to the smoothing operation.

It is another object of the present invention to provide a mechanism of this class which may be easily and quickly operated without necessitating the removal of the operator's hand from the handle of the iron.

Another object of the invention is the provision of a device of this class which will serve to maintain the handle of the iron in cool condition.

Another object of the invention is the provision of a mechanism of this class so constructed and arranged that the water will be delivered to the garment in a fine spray.

Another object of the invention is the provision of a device of this class which will be simple in structure, economical of manufacture, durable, compact and highly efficient in use.

Other objects will appear hereinafter.

The invention consists in the combinations and arrangements of parts hereafter described and claimed.

The invention will be best understood by a reference to the accompanying drawing, which 30 forms a part of this specification in which, Fig. 1 is a side elevational view of the invention.

Fig. 2 is a fragmentary sectional view of the invention taken centrally through the pumping mechanism.

Fig. 3 is a fragmentary central sectional view, illustrating the nozzle used in the invention.

Fig. 4 is a sectional view taken on line 4—4 of Fig. 3.

Fig. 5 is a sectional view taken on line 5—5 of Fig. 3.

In the drawing, I have illustrated the invention as used with a smoothing iron 9 of the electric type. I have dispensed with the usual handle mounted on this type and have embodied the same in my invention. The handle comprises the hollow gripping portion 10, projecting downwardly from which is a supporting brace 11, which is connected by a suitable bolt 12 to the iron 9. The gripping portion 10 terminates at one end in a chamber 13, projecting downwardly and outwardly from which is a shield 14 in spaced relation to the iron 9. Mounted in the chamber 13 is a pump cylinder having threaded into its lower end a fitting 16. The passage 17, formed centrally through the fitting 16, is closed by the

ball valve 18 which is positioned in the recess 19, formed in the inner end of the fitting 16. Slidably positioned in the cylinder 15 is the pump plunger 20 to which is attached the rod 21, which projects outwardly through the guide sleeve 22, so as to be accessible to the operator of the iron. On the outer end of this stem or rod 21, is mounted the cap 23. The location of the cap 23 is such that it is directly beside the thumb of the operator's hand when gripping the portion 10. In order to move the plunger 20 downwardly, the operator has but to lift the thumb and press downwardly on the cap 23 without removing the hand from the gripping portion 10. A spring 24 is positioned in the cylinder 15 and bears at one end against the plunger or piston 20 to retain the parts in the position shown in Fig. 2. The opposite end of the spring 24 bears against the inner end of the fitting 16.

Communicating with and leading outwardly 20 from adjacent the lower end of the cylinder 15 is an outlet pipe or delivery conduit 25 which is angularly turned at its lower end to extend upwardly substantially parallel to the cylinder or barrel 15. At the upper end it is again extended 25 angularly and projected through the wall of the chamber 13.

The construction is such that when the chamber 13 is filled with water and the plunger or piston 20 is pressed downwardly and released, it 30 will move upwardly into the position shown in Fig. 2 in response to the pressure of the spring 24 and the cylinder 15 will be substantially filled with water, the ball 18 moving upwardly off its seat. Then when the plunger 20 is forced downwardly, the water will be expelled through the outlet pipe 25. A filling opening 26 is formed in the upper wall of the structure and a suitable stopper 27 connected by the chain 28 to the pipe 25 is provided for the opening 26, the chain 28 being sufficiently long to permit the removal of the stopper 27 out of the opening 26, so as to 35 permit filling of the chamber 13.

On the outer end of the outlet pipe 25 I provide a nozzle which functions as an atomizer so 45 that the water is emitted from the nozzle in a fine mist or spray. This nozzle comprises the cup-shaped fitting 29 which is pressed over the end 30 of the outlet pipe, as a press fit. In the base of this cup-shaped member is formed the 50 outlet opening 31, from which the water issues. Positioned in the fitting 29 is an atomizer which comprises a plunger 32, having threads 33 and 34 formed thereon. These are double threads 55 extended parallel to each other. This double

formation affords a pair of channels each having their inlet openings or terminations 35 and 36, and each having their outlet openings and terminations 37 and 38, so that the water, passing around the block 32, is rotated and then passes from the threads in a sort of mist, so as to, in this state, issue from the opening 31. With this type of nozzle, the depositing or large drops of water on the fabric is avoided and a very fine 10 sprinkling is effected.

In devices of this type, it has been found that frequently the water would drip from the tip of the outlet end of the pipe onto the iron and seep into the heating element, resulting in a shorting and a burning up of the element. By extending 15 the shield portion 14 well downwardly of the iron this seepage is avoided.

While I have illustrated and described the preferred form of construction, I do not wish to 20 limit myself to the precise details of structure shown but desire to avail myself of such variations and modifications as may come within the scope of the appended claims.

Having just described my invention what I 25 claim as new and desire to secure by Letters Patent is:

1. A device of the class described, adapted for use with a smoothing iron comprising: a hollow handle-forming portion; means for mounting 30 said portion on and in spaced relation to the iron with which used; a chamber communicating with one end of said handle-forming portion and projecting downwardly therefrom at the forward end thereof; a delivery conduit projecting forwardly from said chamber for conducting water therefrom; means for forcing water from said chamber outwardly of said delivery means; a shield projecting downwardly of and outwardly from said chamber-forming portion and adapted 35 for overlying and covering the forward portion 40 of the iron and serving as a deflecting member for deflecting drops of water dropping from said delivery conduit.

2. A device of the class described adapted for 45 use with a smoothing iron and comprising: a hollow handle-forming portion; a chamber-forming portion positioned at the forward end of said handle forming portion and communicating therewith to provide with said handle-forming 50 portion a reservoir for the reception of water; a shield-forming portion on the lower end of said chamber portion and adapted for shielding the forward end of the iron with which used, from drops of water dropping from above; an outlet 55 delivery pipe; and means for forcing water from said reservoir through said outlet delivery pipe.

3. A device of the class described adapted for use with a smoothing iron comprising a hollow handle; a chamber-forming portion positioned at and communicating with the forward end of said handle-forming portion for providing therewith a reservoir for the reception of water; a shield-forming portion on the lower end of said chamber-forming portion and adapted for covering the forward end of the iron with which used; a pump mechanism mounted in said chamber-forming portion; and an outlet delivery pipe communicating with said pump mechanism and directed forwardly thereof for delivering water from said chamber and directing the same upon the fabric in front of the iron. 5

4. A device of the class described adapted for use with a smoothing iron comprising: a hollow handle; a chamber-forming portion positioned at 10 and communicating with the forward end of said handle-forming portion for providing therewith a reservoir for the reception of water; a shield-forming portion on the lower end of said chamber-forming portion and adapted for covering the forward end of the iron with which used; a pump mechanism mounted in said chamber-forming portion; 15 an outlet delivery pipe communicating with said pump mechanism and projecting forwardly therefrom for delivering water from said chamber and directing the same upon the fabric in front of the iron; a plunger in said mechanism; a stem projecting upwardly from said plunger and outwardly of said chamber forming portion; a cap on the outer end of said stem, said cap being positioned adjacent the forward end of said handle-forming portion, accessible to the thumb of the operator when gripping said handle-forming portion. 20

5. A device of the class described, adapted for use with a smoothing iron comprising: a hollow L-shaped body, the leg thereof being adapted to 25 form a handle; means for mounting said L-shaped body on an iron, the base of said L-shaped body being adapted to project vertically upwardly from the forward end of said iron; a concave shield carried by and projecting outwardly from 30 the lower end of the base of said L-shaped body with the concave face directed downwardly and adapted for overlying and covering the forward end of the iron on which mounted, said L-shaped body being adapted for the reception of water; an outlet pipe projecting outwardly through the 35 upper end of the base of said L-shaped body and directed forwardly thereof; and means for forcing water outwardly from said pipe for depositing on the fabric in front of the iron. 40
